(No Model.)

W. H. BURDINE.
Elevator Bucket.

No. 242,878.

Patented June 14, 1881.

UNITED STATES PATENT OFFICE.

WILLIAM H. BURDINE, OF TERRE HAUTE, ASSIGNOR TO WILLIAM P. MYER,
OF INDIANAPOLIS, INDIANA.

ELEVATOR-BUCKET.

SPECIFICATION forming part of Letters Patent No. 242,878, dated June 14, 1881.

Application filed May 5, 1881. (No model.)

To all whom it may concern:

Be it known that I, WILLIAM H. BURDINE, of Terre Haute, in the county of Vigo and State of Indiana, have invented a new and useful Improvement in Elevator-Buckets, which improvement is fully set forth in the following specification and accompanying drawings, in which—

Figure 1 is a front view of the cup. Fig. 2 is a side view of the cup, with the end cut away at the corners to show the construction. Fig. 3 is a view of the bottom. Fig. 4 is an outline of the blank forming the front of the cup, and Fig. 5 is the blank for the rear of the cup.

The object of my invention is to construct a cheap and durable elevator cup or bucket; and to this end it consists in two blanks or parts, one blank of which is bent around to form the front, the ends, and the bottom, and the other blank to constitute the back, all of which will hereinafter be more fully set forth.

In the accompanying drawings, A, Fig. 4, represents a peculiarly formed blank. This is formed of metal, having one straight edge, A', of sufficient length to form the circle of the cup, constituting the front and ends. The ends of this blank B B are projected at an acute angle with the side A', and near the lower ends 30 the angle is still greater, forming the side C. The lower edge, D, of the blank is parallel with the upper edge, A'. The lower edge of the blank is slotted upwardly, as shown at E E, the lines converging toward each other at the top. This forms the size and shape of the bottom of the cup. The dotted line in Fig. 4 represents the point at which the part forming the bottom of the cup is bent inwardly to form the front edge of the base. The triangular part at each side of the line E is then bent inwardly along the dotted lines C' to form the end edges of the base. Along the upper edge, A', a hem, K, is turned down in the opposite direction to the parts described at the lower 45 side of the blank, and between this hem and the blank a metal band, H, is placed. The

blank A containing the band H is then bent to form the cup, as shown in Fig. 1, and the triangular wings, bounded by C C' E, are lapped over the bottom wing, as shown in Fig. 3.

Referring now to Fig. 5, it will be seen that the piece forming the back of the cup has its upper and lower edges parallel and the sides diverging from each other, so that the upper end of the blank is slightly wider than the lower end. The sides G, near the upper end, are cut so as to converge toward each other, and this part is bent back along the line F', so that the upper part, G', will lap over the ends H H' of the band H. The lower edge has a right-angled flange bent forward to embrace the edges B and D of the cup. When thus formed the edges are soldered, constituting a cup which can be cheaply manufactured, and which will be serviceable for any and all purposes desired.

Having described my invention, what I claim is—

1. In an elevator-cup, the blank A, having the upper and the lower edges, A' D, parallel with each other, and the edges B B, forming the ends, converging toward each other, so that the lower part of the blank is about one-half the length of the upper part of the blank, the lower edge of the blank being further provided with slits E E, converging toward each other at the top, as herein specified.

2. In an elevator-cup, the blank A, constituting the front, ends, and bottom of the cup, as shown, in combination with the blank F, constituting the back, soldered together and provided with the band H, as and for the purpose specified.

In testimony that I claim the foregoing I have hereunto affixed my name this 5th day of April, A. D. 1881, in the presence of witnesses.

WILLIAM H. BURDINE.

Witnesses:

JAMES D. BIGELOW,
JOHN C. MYER.
